UNITED STATES PATENT OFFICE.

LYLE CLAPPER, OF TWO HARBORS, MINNESOTA.

LOADING-HOPPER.

1,222,603.

Specification of Letters Patent. Patented Apr. 17, 1917.

Application filed September 25, 1916. Serial No. 122,078.

To all whom it may concern:

Be it known that I, LYLE CLAPPER, a citizen of the United States, and resident of Two Harbors, in the county of Lake and State 5 of Minnesota, have invented certain new and useful Improvements in Loading-Hoppers, of which the following is a specification.

My invention relates to hoppers, and particularly to the mechanism for controlling 10 the doors thereof.

It is frequently undesirable or impractical to build loading hoppers in such manner as to provide sufficient head room therebeneath in order to permit of the door or 15 closure being hinged in the usual manner. If the door is hinged in such manner it is likely to interfere with the wagon or other receptacle intended to receive the material discharged from the hopper.

20 An object of my invention is to provide a hopper door controlling mechanism wherein in one edge of the door is dropped a short distance to free the load, whereupon the door is moved bodily sidewise and vertically, its 25 final position being entirely clear of the opening. This permits a full load to be received out of the hopper, the material being heaped to practically the level of the bottom edge of the hopper. This is something 30 which could not be done if the door were permitted to swing in the usual manner.

Furthermore, an object is to provide a door-supporting mechanism, which, when in closed position, shall tend to retain the door 35 in such position without further fastening devices; *i. e.*, the greater the load imposed on the door, the greater the tendency for the door to be maintained in closed position.

The desired objects are attained by supporting the door upon two pairs of links, 40 one link in each pair being articulated, together with means adapted to act first to break the toggle in the articulated link, whereby one edge of the door is permitted 45 to drop, then bodily moving the door transversely of the opening by engaging the other or rigid link.

The invention will be more readily understood by reference to the accompanying 50 drawings, wherein—

Figure 1 is a side elevation of an adaptation of my invention to a small loading hopper;

Fig. 2 is an end view thereof;

55 Fig. 3 is a view similar to Fig. 1 showing the first step in the door-opening action;

Fig. 4 is a similar view showing the next step, and

Fig. 5 is a fragmentary sectional view showing the form of connection between the 60 operating bell crank and the shaft.

The hopper, which I have designated 10, may be of any approved form. It may be connected to a railway car, a side wall of which I have indicated at 11, by means of 65 the hook 13, which engages over the top of the car and the brace 14 which engages the side of the car.

The hopper is provided with a bottom 70 opening which is closed by a door 15. This door is supported by two pairs of links, one pair on each side of the hopper. One link of each pair is articulated and one link of each pair is rigid. The rigid link is lettered 16 and is pivoted at its upper end on 75 the transverse shaft 17. The door is hinged at 18 to the lower end of the link. For the purpose of description, let it be assumed that the center-line 19 represents the articulated link, this line extending through the 80 center of the shaft 17 and the pivot point 20 at the connection to the door 15. It will be seen, therefore, by reference to the center-lines 19 and 21, that the door is supported by what might be termed an A-frame at each 85 side of the hopper.

However, the articulated link is of peculiar construction and comprises the complementary short links 22, 23, 24, all of which are bent to an obtuse angle and are joined end to end. The lower end of link 22 is hinged to the door at the point 20, whereas the upper end of the link 24 is pivoted to the bell crank 25, the center of rotation of which is the shaft 17. The other arm of this bell crank is in the form of an operating lever 26. A key 27, shown in dotted lines in Fig. 1 and in full lines in Fig. 5, serves to connect the bell crank rigidly to the shaft 17. The key 27 also connects the link 16 to the shaft, with capacity for considerable lost motion by reason of the slot 28, best shown in Fig. 5, located in the hub of the link 16. 90 95 100 105

Not only are the links 22, 23, joined end to end, but the link 23 is hinged at an intermediate point to the end of a bracket 29, which is fixed to the link 16. The point of connection of the link 23 to the bracket 29 is preferably on the line 19—that is a neutral point with relation to the maintenance 110 of the toggle joint. However, it will be noted that a line, such as I have indicated at

30, which passes through the point of connection between the link 22 to the door and to the link 23, falls outside of the line 19; and furthermore that a line such as we have 5 lettered 31, extending through the points of connection of the link 24 at its two ends, also falls outside of the line 19. Therefore, when the parts are in the position of Fig. 1, the tendency is for the parts to remain in 10 such position. In order to break the toggle, it is necessary to actuate the lever 26. Rotation of the bell crank will tend to bring the line 30 into parallelism with the line 19, and as soon as out of parallelism on the 15 opposite side to that shown in Fig. 1, the door will drop to the position of Fig. 3, bringing the lever 26 to a vertical position. At that point the key 27 has moved to the extremity of the slot 28 and engages the 20 link 16. Further angular movement of the lever 26 causes a similar movement of the link 16, and the bodily lifting of the door to the position shown in Fig. 4. To accomplish this result, the door has swung downward only to the extent shown in Fig. 3. It will be seen, therefore, that a container 25 located beneath the hopper may be filled to a level even with the bottom of the hopper, all without interference with the door.

30 Upon the release of the operating lever 26, the door will return to substantially the position of Fig. 3 by gravity; then by restoring the lever to the position of Fig. 1 the parts are replaced as shown in that figure.

35 I claim:

1. In a loading device, the combination of a hopper, a closure for the bottom opening therein, a pair of links for supporting said closure, one of said links being articulated, 40 and a lever for first breaking said articulated link and then acting to bodily move said closure transversely of the opening, substantially as described.

2. In a device of the class described, the 45 combination of a container having a bottom opening, a closure for said opening, a pair of links for supporting said closure, one of said links being articulated and the other link being rigid, and means constructed to first engage said articulated link and break the same, then to engage said rigid link and to move said closure bodily transversely of the opening, substantially as described.

3. In a device of the class described, the 55 combination of a container having a bottom opening, a closure for said opening, a pair of links for supporting said closure, one of said links being composed of a plurality of parts which are hinged together, a bracket 60 fixed to one of said links and providing a fulcrum for one of the parts of the divided link, and means for first acting upon said divided link to permit of the dropping of one edge of the door or closure, then acting 65 upon the other link to cause the bodily movement of the door, substantially as described.

4. In a device of the class described, the combination of a hopper having a bottom opening, a horizontal door for said opening, 70 a pair of links at each side of said hopper, each pair of links having a common pivotal point near the upper portion of the hopper, one of each of said pairs of links being articulated and the other of each of said pairs 75 of links being solid, and a lever acting to break both of said articulated links, then to engage said solid link and bodily move the door away from the opening, substantially as described.

5. In a loading device, the combination of a hopper, a door for the bottom opening therein, a rigid link for supporting one side of said door, a compound link for supporting the other side of the door, said compound link being composed of at least three supplementary links, and a bracket carried by said rigid link and providing a fulcrum for one of said supplementary links, substantially as described.

6. In a loading device, the combination of a hopper, a door for the bottom opening therein, a rigid link for supporting one side of said door, a compound link for supporting the other side of the door, said compound link being composed of at least three supplementary links, a bracket carried by said rigid link and providing a fulcrum for one of said supplementary links and a manually-operable bell crank mounted to first 100 act upon said compound link and then upon said rigid link, substantially as described.

Signed at Two Harbors, Minn., this 18 day of September, 1916.

LYLE CLAPPER.
